BALANCING SNAKE FIGURE TOY OR THE LIKE

Evan H. Berlin, 119 Dunn Ave., Lake City, Pa. 16423

Filed July 5, 1973, Ser. No. 376,721

Term of patent 14 years

Int. Cl. D21—01

U.S. Cl. D34—2 R

FIG. 1 is a side elevational view of a snake figure toy showing my new design;

FIG. 2 is a rear elevational view thereof;

FIG. 3 is a front elevational view thereof; and

FIG. 4 is a top plan view.

The bottom is hemispherical.

I claim:

The ornamental design for a balancing snake figure toy or the like, as shown and described.
